UNITED STATES PATENT OFFICE.

AXEL A. STROM, OF AUSTIN, ILLINOIS.

CHAIR FOR RAILROAD-TRACKS.

SPECIFICATION forming part of Letters Patent No. 332,760, dated December 22, 1885.

Application filed May 26, 1885. Serial No. 166,708. (No model.)

To all whom it may concern:

Be it known that I, AXEL A. STROM, a citizen of the United States, residing at Austin, in the county of Cook and State of Illinois, have 5 invented certain new and useful Improvements in Chairs for Railroad-Tracks; and I hereby declare the following to be a full, clear, and exact description of the same.

My invention, though it is readily adaptable, as will hereinafter appear, to other analogous uses, is designed particularly for use as a switch-chair, or, as it is more commonly called, a "head-chair." Devices hitherto used for this purpose present a construction somewhat 15 resembling mine, but are designed to operate in securing the ends of the rails in position (in which the oscillatory section of rail or switch-rail is made to coincide with the one or the other for the purpose of switching) by 20 the flanges of the rails, which enter recesses or sockets provided to receive them, and formed with the upper surface of the plate on the under side of the usual cross-bar, which recesses have vertical openings or slots on their 25 upper sides considerably wider than the necks of the rails to receive which they are provided. This manner of construction presents serious objections, one being due to the fact that the rail-flanges differ considerably in width, even 30 in rails of the same weight, necessitating frequent change in the manufacture (ordinarily by casting) of the chairs of the width of the sockets, whereby they shall afford snug fit to the flanges, which they are to receive, to hold 35 the ends of the rails with sufficient rigidity, and another being that one or the other flange of a rail, at the part contained within a socket of the chair, owing to the enormous strain continually being exerted upon it, with the 40 weight and momentum of bodies passing over it, is liable to and frequently does become broken, whereby the rigidity of its hold is destroyed, permitting it to be forced outside of the limit of throw of the switch, and thus rendering liable 45 disastrous consequences.

The foregoing objections are the inevitable result of holding rails in position within switch-chairs by their flanges. I overcome these objections by holding the rails at their 50 necks, which, besides permitting a chair of increased strength and durability to be pro-

vided, and since there is not by any means the difference in thickness of the necks of the rails that there is in the width of flanges, allowing chairs having the parts of uniform dimensions 55 to be employed, generally affords greater and by far more reliable and lasting rigidity to the ends of the rails in their positions within the chairs.

My invention consists in the construction 60 hereinafter described and claimed.

Referring to the drawings, Figure 1 is a plan view of a railroad-switch provided with my improvement; Fig. 2, a vertical transverse section taken on the line 22 of Fig. 1, showing 65 the preferred construction of the cross-bar of my improved chair, and showing only one rail in position, the other being omitted to avoid obscuring of features hereinafter described; Fig. 3, a similar view to that shown in Fig. 2, 70 representing a modified construction of the cross-bar; and Figs. 4 and 5, perspective views of the chair, illustrating, respectively, the preferred and modified construction of the cross-bar. 75

A is a flat, preferably rectangular, metal plate, to be secured upon a railroad-tie. B is the cross-bar, which may be formed as a part of the plate A or attached to it in any manner that will afford the requisite security, and is provided with transverse slots t through one lateral edge and extending toward the opposite lateral edge a sufficient distance to leave a backing of a thickness to afford requisite strength to the bar and stops for the ends of the main rails, 80 and the slots t lead into chambers or sockets s, sufficiently large to accommodate the flanges r of any of the usual dimensions of rails C. The distance from the center of one slot s to that of the other corresponds with the limit 85 of throw of the switch-rail C', and the width in cross-section of each slot is such as will readily permit the entrance into it of the rail-neck q, the sides of which would be forced against the adjacent side of a slot by sufficient 90 strain upon the top of the rail, thereby affording a stop which prevents displacement of the rail. 95

The construction of the cross-bar B (shown in Figs. 3 and 5) affords a very desirable form 100 of this feature of my invention, comprising a solid oblong metal bar provided with the nec-

essary form of slots *t*, and hollowed out below the slots, as shown, to produce the sockets *s*. The preferred form, however, and that which, owing to its construction, affords the greater strength, since the sockets are formed without reducing the thickness of metal, and since the rail is supported higher upon the neck, is that shown in Figs. 1, 2, and 4, in which the slots are formed by slitting the bar transversely a distance to leave a backing, to produce stops for the main rails and of desired thickness to afford requisite strength without removing, as may be required, any metal in producing the slits, when the metal on each side of a slit is bent in a heated state upward to an extent necessary to afford a socket, *s*, and slot *t*, of desired dimensions, without severing the edges of the parts forming the roofs of the sockets from the backing. This form may, also, like

the modification hereinbefore described, be 20 made in separate pieces.

There is no reason why my improved device shall not be used for other purposes than merely the purpose of a switch or head chair.

What I claim as new, and desire to secure by 25 Letters Patent, is—

A switch or head chair comprising, in combination, a plate, *A*, and a cross-bar, *B*, formed in one or more parts and secured upon the plate *A*, and slitted transversely part way 30 across, and having the edges on each side of a slit bent upward to afford slots *t* and sockets *s*, closed on one side, substantially as described.

AXEL A. STROM.
